N-ALKYL-N-(SULFOPHENYLTHIO)ALKYLAMINOANILINES

William Howells Vinton, Parlin, N. J., assignor to
E. I. du Pont de Nemours and Company, Wil-
mington, Del., a corporation of Delaware

No Drawing. Application May 5, 1951,
Serial No. 224,823

3 Claims. (Cl. 260—510)

1

This invention pertains to a new class of N-substituted aminoaniline derivatives. More particularly it pertains to N-alkyl-N-(sulfo-phenylthioalkyl) aminoanilines. These compounds are useful as photographic developing agents.

Various arylendiamines have been used as photographic developing agents, but the most important of them, namely, para-phenylenediamine and its lower N,N-dialkyl derivatives have the disadvantage that they are readily absorbed by the skin and give rise to dermatitis. Since these agents are strong photographic developers and readily couple with color formers during the development of latent silver halide images to produce quinoneimine or azomethine dye images in situ with the silver images, they are used in most commercial processes of color photography. The compounds, however, due to their toxicity constitute a health hazard in photographic developing laboratories.

An object of this invention is to provide a new class of photographic developing agents. A further object is to provide a new class of photographic developing agents which are useful in chromogenic development and are free from toxic effects. The more specific object is to provide a new class of N-alkyl-N-(sulfo-phenylthioalkyl) aminoanilines. Still other objects will be apparent from the following description of the invention.

The new compounds of this invention may be represented by the following general formula:

where R is a hydrogen atom or an alkyl or substituted alkyl group or an alkoxy or substituted alkoxy group; n is a positive integer from 2 to 10, m is 1 or 2 and alkyl contains from 1 to 6 carbon atoms. Among the useful alkyl radicals for R there may be mentioned $-\text{CH}_3$, $-\text{C}_2\text{H}_5$, $-\text{CH}(\text{CH}_3)_2$ and among the useful substituted alkyl radicals R there may be mentioned $-\text{CH}_2\text{OH}$ and $-\text{CH}_2\text{Cl}$. Suitable specific alkoxy radicals for R include $-\text{OCH}_3$, $-\text{OC}_2\text{H}_5$ and $-\text{OCH}(\text{CH}_3)_2$. R, however, preferably is hydrogen or an unsubstituted alkyl or alkoxy radical of 1 to 3 carbon atoms.

It is important that the tertiary nitrogen atom and the sulfophenyl group in the above compounds be separated by at least two methylene (CH_2) groups in order to obtain a high degree

2

of photographic development. The compounds where n is 3 to 6 and alkyl contains 1 to 4 carbon atoms are preferred. When n is greater than 10 the compounds still possess some developing properties but are less satisfactory than compounds covered by Formula I because the developer has a slow rate of diffusion into a colloid silver halide emulsion layer and it is more difficult to wash such compounds out of the colloid silver halide emulsion layers.

The compounds of Formula I may be prepared by the following series of chemical reactions: (a) preparation of an N-alkyl-N-(phenylthioalkyl) aniline by reaction of an omega-halogen substituted alkyl phenylthioether containing the halogen and thioether groups on the opposite ends of the straight chain alkylene radical with an N-alkylaniline, e. g., N-methylaniline, N-ethylaniline or N-butylaniline. This reaction is usually carried out under neutral to alkaline conditions; (b) preparation of N-alkyl-N-(omega-sulfo-phenylthioalkyl) anilines by the reaction of the tertiary amine derivative obtained in step (a) with a sulfonating agent, e. g., hot concentrated sulfuric acid; (c) preparation of the corresponding p-nitroso-N-alkyl-N-(omega-sulfo-phenylthioalkyl) aniline by reaction of the compound obtained in step (b) with nitrous acid; and (d) reduction of the nitroso compound obtained in step (c), e. g., with iron or catalytically with hydrogen to the corresponding amine having the general Formula I.

When N-methyl-m-toluidine, N-ethyl-m-toluidine, N-methyl-m-anisidine, N-ethyl-m-anisidine, or similarly nuclear substituted N-alkyl anilines are used in place of the N-alkyl aniline in the above syntheses one obtains the correspondingly substituted developers.

This invention will be further illustrated by the following examples. They exemplify suitable specific methods for the preparation of the compounds and illustrate their uses and properties but are not intended to limit the invention.

EXAMPLE I

45 N-ETHYL-N-(GAMMA-DISULFOPHENYLTHIOPROPYL)-
P-PHENYLENEDIAMINE HYDROCHLORIDE

A. *Gamma-chloropropyl phenyl thioether*

50 An aqueous solution of 40 grams (1.00 mol) of sodium hydroxide in 125 milliliters of water was added with stirring over a half hour period to a boiling mixture of 157 grams (1.00 mol) of trimethylene chlorobromide, 110 grams (1.00 mol) of thiophenol and 375 ml. of water. The mixture

55

was refluxed for 3½ hours (whereby the NaOH was consumed), cooled to room temperature, saturated with sodium chloride, and extracted twice with diethyl ether. The solution was dried over anhydrous sodium sulfate, the diethyl ether distilled at atmospheric pressure, and the residual oil was distilled in a precision still of about 15 theoretical plates to give 169.3 grams (91% of theory) of gamma-chloropropyl phenyl thioether boiling at 124–125°/7 mm. (n_D^{26} , 1.5714).

B. *N*-ethyl-*N*-gamma-phenylthiopropylaniline

A mixture of 168 grams (0.90 mol) of the compound prepared above and 242 grams (2.00 mols) of redistilled *N*-ethylaniline was stirred on a steam bath under nitrogen for 44 hours; 36 grams of sodium hydroxide in 200 ml. of water was stirred with the cooled reaction mixture and the top organic layer was separated, dried over potassium hydroxide, and distilled under nitrogen from a precision still to give 99.0 grams of a product boiling at 191–192° C. at 3 millimeters ($n_D^{21.5}$, 1.6072).

C. *N*-ethyl-*N*-(gamma-disulfophenylthiopropyl)-aniline

Ninety-eight grams of the diamine prepared above was sulfonated in the manner described under II-E. The reaction product was obtained as a thick oil which did not crystallize.

D. Nitrosation of *N*-ethyl-*N*-(gamma-disulfophenylthiopropyl)-aniline

The *N*-ethyl-*N*-(gamma-disulfophenylthiopropyl)-aniline obtained in step C (140 grams, 0.4 mol) was nitrosated by the method given in A. H. Blatt: *Organic Syntheses Collective Volume II*, page 223, John Wiley & Sons, New York 1943. The nitroso compound separated as a dark red tar which was finally crystallized to a red solid weighing 113 grams (68.0% of theory).

E. Reduction of *p*-nitroso-*N*-ethyl-*N*-(gamma-disulfophenylthiopropyl)-aniline

Forty grams of iron powder was added in small portions to a solution of 60.5 grams of the above prepared disulfonic acid in 168 milliliters of concentrated hydrochloric acid and 500 ml. of water. The temperature was kept below 35° C. with external cooling. After the nitroso color had been destroyed, the temperature was raised to 50° C. for 15 minutes and the unreacted iron was filtered with suction, the solution was cooled and made strongly alkaline by adding a 10% sodium hydroxide solution. The heavy gelatinous precipitate was filtered with suction (very slow filtering) through a pad of shredded filter paper. The filter cake was extracted with boiling water containing a small amount of sodium hydrosulfite until only a weak test for color developer was obtained with 3-methylsalicylanilide. The solution was acidified to Congo red paper, evaporated to dryness in a nitrogen atmosphere and under reduced pressure from a hot water bath kept below 50° C. The 39.7 grams of dry solid was digested with 100 ml. of boiling anhydrous methanol, filtered with suction and the digestion was repeated 12 times with 50 ml. portions of methanol. The 8.7 grams of methanol insoluble residue still gave a faint color developer test. The methanol was concentrated under reduced pressure in a nitrogen atmosphere from a hot water bath to about 150 ml. The 4.49 grams of grey solid which had separated was filtered with suction, washed with cold methanol and with ether. The filtrate was

run in a fine stream, with mechanical stirring into 500 ml. of ether, and the mixture was cooled to about 30° C. solid CO₂. The solid was filtered and dried in a vacuum dessicator; weight 17.4 grams.

Anal. calcd. for C₁₇H₂₂N₂S₃O₆: N, 6.28; S, 21.53. Found: N, 6.27, 6.56; S, 21.78, 21.67.

EXAMPLE II

10. *N*-Ethyl-*N*-(Epsilon-p-Sulfophenylthioamyl)-p-Phenylenediamine

A. 5-chloroamyl acetate

5-Chloroamyl acetate (B. P. 107–110°/25 mm., 15 n_D^{20} , 1.4373) was prepared by the method described by Cason et al. (J. Org. Chem., 14, 41 (1949)).

B. Pentamethylene chlorobromide

Pentamethylene chlorobromide B. P. (94–99° C./26 mm, n_D^{20} 1.4862) was prepared by reacting chloroamyl acetate with hydrobromic acid by the method described by Cason et al. (loc. cit.).

C. Epsilon-chloroamyl phenyl thioether

A solution of 55.2 grams of sodium hydroxide in 175 ml. of water was added with stirring over a 45 minute period to a refluxing mixture of 256 grams of pentamethylene chlorobromide, 152 grams of thiophenol and 325 ml. of water. The mixture was refluxed and stirred for 3½ hours and left standing overnight at room temperature. The upper organic layer was separated, dried over CaCl₂, and fractionated through a 12 mm. x 50 cm. wire gauze screen column at a reflux ratio greater than 10:1 and using a nitrogen bleed.

The yield of epsilon-chloroamyl phenyl thioether distilling at 114–116° at 2.5 mm. (n_D^{20} 1.5590) was 72 percent of theory based on the thiophenol used.

D. *N*-ethyl-*N*-epsilon-phenylthio-amylaniline

A mixture of 213 grams (0.99 mol) of epsilon-chloroamyl phenyl thioether and 254 grams (2.2 mols) of *N*-ethylaniline was stirred under nitrogen for 50 hours at 155–165° C. The reaction mixture was then cooled in ice and 43 grams of sodium hydroxide in 200 ml. of water was stirred into it to liberate the free base from *N*-ethyl-aniline hydrochloride. The organic layer was separated, dried over potassium hydroxide and fractionated through a precision column of about 15 theoretical plates. The 194-gram cut boiling at 194–195° C./3 mm. (n_D^{20} 1.6033) corresponds to a 66 percent yield of *N*-ethyl-*N*-epsilon-phenylthio-amylaniline.

E. *N*-ethyl-*N*-(epsilon-sulfophenylthio-amyl)-aniline

Sixty grams (0.200 mol) of amine prepared above was sulfonated by adding it dropwise with stirring to 85 ml. of concentrated sulfuric acid at 100–110° C. over a 20 minute period and then stirring at 100–110° C. for an additional 10 minutes until the solution was completely soluble in 5% sodium hydroxide solution. The reaction product separated as a white taffy-like material which crystallized upon long working with 10 changes of ice water; weight 81.2 grams (83.5 percent of theory), M. P. 123–125° C. It was insoluble in water, acetonitrile, pyridine, nitroethane, dioxane, ethyl acetate, tetrahydrofurfuryl alcohol, and in methanol. It was soluble in concentrated sulfuric acid and in dilute sodium hydroxide.

F. *Diazo coupling of N-ethyl-N-sulfo-phenylthio-amyylaniline with p-toluidine*

A diazonium chloride solution, prepared from 8.2 grams (0.076 mol) of p-toluidine, was added with stirring to a solution of 36 grams (0.076 mol) of the amine in 200 ml. of water containing 10 grams of sodium hydroxide. The temperature of both solutions was below 10° C. The mixture became dark magenta immediately but no solid separated. After the mixture had stood for about 15 minutes, 20 grams of sodium hydroxide dissolved in 50 ml. of water was added and the mixture was allowed to stand in ice for an hour longer. Some dye separated as a viscous, red, oily paste. This did not become crystalline upon standing overnight in the ice chest, so the mixture was diluted with an equal volume of water, heated to 50° and reduced with sodium hydro-sulfite until a test portion no longer showed the presence of an azo dye. The yellow solution was filtered to remove p-toluidine which had separated and then acidified with acetic acid. The gummy solid which separated was dissolved in dilute sodium hydroxide, the undissolved sulfur was filtered, and the solid was reprecipitated with acetic acid as a light brown powder. The process was repeated again and the solid was dried in a vacuum desiccator; weight 12.10 grams, M. P. 237° C.

The compound is soluble to the extent of about 8.5 grams per liter of water containing a stoichiometric amount of sodium hydroxide. It is possible to prepare a developer solution containing an adequate amount of the color developer by using potassium carbonate or sodium carbonate or other alkalies by the aid of a hydroscopic wetting agent, e. g., sodium dodecyl sulfate. At pH below 3.0, its cyan dye showed a sharp indicator effect (turning more blue).

Anal. calcd. for $C_{19}H_{26}N_2O_3S_2H_2O$: N, 6.79; S, 15.56. Found: N, 6.16, 6.02; S, 15.77, 16.05.

By substituting equivalent amounts of ethylenechlorobromide or other polymethylene chlorobromides, e. g., tetramethylene chlorobromide, hexamethylene chlorobromide, heptamethylene chlorobromide, monomethylene chlorobromide and decamethylene chlorobromide for the trimethylene chlorobromide of Example I or the pentamethylene chlorobromide of Example II still other homologous compounds which fall under generic Formula I above can be prepared.

Similarly by substituting for the N-ethylaniline of Examples I and II or in similar reactions using the chlorobromides in the preceding paragraph the other N-alkylanilines listed before the above working examples one can make still other homologous compounds which come under structural Formula I.

Among the suitable compounds which can be made as just taught are:

- N-methyl-N-(γ - sulfophenylthiopropyl) - p - phenylenediamine
- N-methyl-N-(γ - disulfophenylthiopropyl) - p - phenylenediamine
- N-ethyl - N - (γ - sulfophenylthiopropyl) - p - phenylenediamine
- N-ethyl-N - (γ - disulfophenylthiopropyl) - p - phenylenediamine
- N-propyl-N - (γ - sulfophenylthiopropyl) - p - phenylenediamine
- N-propyl-N - (γ - disulfophenylthiopropyl) - p - phenylenediamine
- N-isopropyl - N - (γ - sulfophenylthiopropyl) - p - phenylenediamine

- N-isopropyl-N-(γ - disulfophenylthiopropyl) - p - phenylenediamine
- N - butyl - N - (γ - sulfophenylthiopropyl) - p - phenylenediamine
- N - butyl - N - (γ - disulfophenylthiopropyl) - p - phenylenediamine

and the corresponding compounds which have in place of methyl, ethyl, propyl, isopropyl and butyl an alkyl-substituted butyl, amyl or hexyl radical.

The photographic developing properties of the compounds of this invention are exemplified by the compound of Example I (identified as A) in comparison with p-aminodiethylaniline (identified as B) and are shown in the following table:

TABLE
Monolayer coatings

	Block Speed		Gamma		Base+Fog	
	B	A	B	A	B	A
Cyan	5.0	4.7	3.70	4.02	0.13	0.13
Magenta	6.7	6.4	2.14	2.28	0.20	0.19
Yellow	6.0	5.0	1.93	1.42	0.09	0.08

The equimolar developer solutions used to obtain the results in the above table had the following compositions:

	I		Grams.
	Developer A	Developer B	
Na ₂ SO ₃	-----	-----	10.0
Na ₂ CO ₃ .H ₂ O	-----	-----	29.25
KBr	-----	-----	2.0
Water to make 1 liter.	-----	-----	-----
	II		Grams.
	Developer B	Developer A	
Na ₂ SO ₃	-----	-----	10.0
Na ₂ CO ₃ .H ₂ O	-----	-----	29.25
KBr	-----	-----	2.0
Water to make 1 liter.	-----	-----	-----

In the foregoing table the cyan, magenta and yellow coatings were dispersions of light-sensitive silver iodobromides in polyvinyl acetal color formers of aromatic halides of the type described in U. S. Patents 2,397,864, and 2,380,033 and U. S. applications Ser. Nos. 9,330, filed February 19, 1948, now U. S. Patent 2,513,190 and 29,921, filed May 28, 1948, now U. S. Patent 2,538,257. In the table gamma refers to the development factor and fog relates to the density of development in the unexposed portion of the photographic film. Block speed is an arbitrary figure indicating the speed of the developer. If a developer has a block speed one unit less than another, this means that the photographic film will require about twice the degree of exposure to give an image of the same density as the second under the same conditions of development. Gamma is defined in Neblette, "Photography" page 412 (published by D. Van Nostrand Company, 1942). Values of the block speed and/or gamma comparable or superior to those of the commercial developer, p-aminodiethyl-aniline, are important. Increases are shown in the table for certain of these values. Particularly important is the fact that the new developers cause less fog than the p-aminodiethylaniline.

The compounds when employed as photographic developing agents may be used as the free acid or as a suitable derivative of the sul-

fonic acid group, e. g., the alkali metal or ammonium salt, according to the solubility requirements of the system. The developing agents may be used in developer formulations containing color formers for color development of exposed silver halide contained in gelatin or synthetic water-permeable colloid binding agents for silver halide grains. They may be used in the color development of photographic films containing immobile color formers in the light-sensitive silver halide emulsion layers, particularly films of the type described in U. S. Patent No. 2,397,864.

The novel developing agents of this invention can be admixed with other conventional constituents of photographic developers including alkaline materials, e. g., sodium carbonate, potassium carbonate, sodium hydroxide, lithium hydroxide; preservatives, e. g., lithium, sodium, potassium, and ammonium sulfites and bisulfites, amine salts of sulfurous acids, for example, triethanolamine sulfite, morpholine sulfite, trimethylbenzylammonium sulfite; restrainers, e. g., sodium, potassium, and lithium chlorides, bromides and iodides, ammonium bromide; other ingredients, e. g., emulsion hardeners, for example, potassium aluminum sulfate, chrome alum; buffering salts, e. g., disodium hydrogen phosphate, sodium metaborate, borax. The solutions or compositions may be made in two parts, if desired, which are mixed at the time of use.

The compounds of Formula I where n is 5 to 10 are more insoluble than when n is 2, 3 or 4 and in order to get a sufficient amount in solution it may be necessary to use a small amount, e. g., 0.05 to 2.0% by weight of the solution of a hydrotropic wetting agent. Among the useful agents of this type are saponin, alkali metal salts of mono-, di- and tri-alkyl naphthalene sulfonic acids, sodium methylene bis naphthalene sulfonic acids; alkali metal alkyl sulfates and alkali metal alkylsulfonates of 8 to 18 carbon atoms, etc. Still other hydrotropic agents are

described in Ullman "Encyclopaedie der Technischen Chemie," 2nd ed., vol. IX, page 808.

Another advantage of this invention resides in the fact that the compounds are much less toxic or allergenic in contact with human skin than p-aminodiethylaniline. This is of commercial importance because one of the principle disadvantages of color developers is their irritating effect on the skin.

The compounds of Formula I, however, are not limited in their use as photographic developing agents. To the contrary, they are useful chemical intermediates and may serve as a basis for the preparation of various other chemical compounds, e. g., amides, etc., which may find use as dyes or dye intermediates.

As many widely different embodiments of this invention can be made without departing from the spirit and scope thereof, it is to be understood that the invention is not to be limited except as defined by the claims.

What is claimed is:

1. The chemical compounds of the general formula:

30 where R is a member taken from the group consisting of hydrogen, alkyl radicals of 1 to 3 carbon atoms and alkoxy radicals of 1 to 3 carbon atoms, alkyl contains 1 to 6 carbon atoms, n is a cardinal number from 2 to 10 inclusive and m is an integer from 1 to 2.

2. p-Amino-N-ethyl-N-(gamma-disulfophenylthiopropyl)-aniline.

3. p-Amino-N-ethyl-N-(epsilon-p-sulfophenylthioamyl)-aniline.
